Patented Sept. 19, 1922.

1,429,344

UNITED STATES PATENT OFFICE.

JOSEPH D. HIPPOLITUS, OF NEW HAVEN, CONNECTICUT.

WINDOW SCREEN.

Application filed November 1, 1920. Serial No. 421,165.

To all whom it may concern:

Be it known that I, JOSEPH D. HIPPOLITUS, a citizen of the United States, residing at New Haven, in the county of New Haven, 5 State of Connecticut, have invented certain new and useful Improvements in Window Screens; and I do hereby declare the following to be a full, clear, and exact description of the invention, such as will enable 10 others skilled in the art to which it appertains to make and use the same.

This invention relates to window screens.

The object of the invention is to provide an improved construction of window screen 15 which will render same easily associated with an ordinary window and when so associated will cover the open space left as the lower sash is raised and will automatically wind upon a suitable roller element when 20 the sash is lowered.

A further object of the invention is to provide a window screen of the type named which can be adjusted with respect to its 25 width whereby same can be made to conform to different sized windows.

With the above and other objects in view the invention consists in the details of construction and in the arrangement and combination of parts to be hereinafter more fully 30 described and particularly pointed out in the appended claim.

In describing the invention in detail reference will be had to the accompanying drawings wherein like characters of reference 35 denote corresponding parts in the several views, and in which—

Figure 1 is a view in elevation of a window having the improved screen associated therewith, the lower sash being partly elevated;

Figure 2, a longitudinal section of the roller element of the improved screen;

Figure 3, a view looking at the left hand end of the roller element in Figure 2;

Figure 4, a view looking at the right end of the roller element in Figure 2;

Figure 5, a view of the anchor member of the screen, and

Figure 6, a section on the line 6—6 of Figure 5.

Referring to the drawings A indicates the window frame and B the window sash. The sash B carries spaced brackets 10 and 11 which support the roller element C of the 55 improved screen after the fashion of mounting a window shade.

This element C comprises a main roller portion 10 provided with a longitudinal recess 11' opening through one end thereof. Mounted in the inner end of the recess 11' is a bearing block 12 in which is rotatably mounted one end of a rod 13. The other end of this rod is rotatably mounted in a disk 14 which closes the outer end of the recess 11'. The outer end of the rod 13 has fixed thereon 60 a ratchet 15 with which cooperates pawls 16 mounted on the disk 14 for a purpose that will presently appear. Disposed within the recess 11' and encircling the rod 13 is a spring 17 one end of which is anchored to 65 the bearing 12 and the other end to the rod 13. By this construction it will be obvious that the tension of the spring 17 can be varied and a desired tension maintained by co-operation of the pawls 16 with the ratchet 70 15. Projecting from the end of the main roller 10 are longitudinally extending diametrically opposite arms 18 and 19 provided on their inner faces with corresponding grooves 20 in which are slidably engaged respectively the ends of a pin 21 which is passed through and secured to a 75 rod 22, the latter being disposed between and parallel to the arms 18 and 19. The outer end of the rod 22 carries a journal stud 80 23 adapted to rotatably engage in the bracket 11 while the outer end of the rod 13 is non-rotatably engaged in the bracket 10. It will be noted that owing to adjustability of the 85 rod 22 the roller element C can be readily 90 adapted for mounting on window sashes of different widths. Attached to the main roller 10 is one end of a screen section 24, while the corresponding end of a screen section 25 is secured to the rod 22 and said 95 last named screen section passes through a slot 26 in the arm 19.

The anchor element of the screen is indicated at D and comprises sections 27 and 28. The former is provided with a groove 29 in 100 which is slidably engaged a rib 30 on the section 28. By this construction it will be obvious that the sections 27 and 28 can be adjusted longitudinally of each other to conform to the adjustment of the rod 22. The 105 outer ends of the sections 27 and 28 carry studs 31 respectively which are adapted to be engaged in prepared recesses in the window stop. The lower ends of the screen sections 24 and 25 are secured respectively to 110 the sections 27 and 28 of the anchor element D.

2

It will be observed that the extension rod which is housed in a cavity formed longitudinally in one end of the spring roller section of the device and which while being adapted for longitudinal adjustment to adapt the length of the roller to the width of the window, is keyed to the spring roller section so as to rotate therewith, is disposed axially with relation to the spring roller section so that this outer extremity is adapted to carry one of the journal studs with which the opposite ends of the roller are equipped, for engagement with the brackets on the sash, and therefore the extension rod performs the dual function of an extension of the roller to carry the movable section of the screen web and also an extension of the journal carrying element of the roller, whereby the operation of adjusting the extension rod adjusts the width of the screen web and also the length of the roller to adapt them for a modified width of the window.

What is claimed is:

An extension window screen of the type

having extensible roller and anchoring members connected by a sectional screen web of which the members overlap at their adjacent edges, wherein the roller member consists of a spring roller section having at one end an axial tension rod longitudinally adjustable with relation to the spring roller section and keyed thereto for joint rotary movement and having one end of one of the screen web sections attached to and adjustable therewith, the spring roller section being cavitated longitudinally to house said rod and being slotted for the passage of the screen web section therethrough, and the journal studs of the roller being carried by the remote ends, respectively, of the spring roller section and said extension rod.

In testimony whereof, I affix my signature, in the presence of two witnesses.

JOSEPH D. HIPPOLITUS.
